CONVEYER

Oren E. Bogart and Ralph A. Miller, Yakima,
Wash.

Application June 11, 1937, Serial No. 147,764

1 Claim. (Cl. 198—219)

This invention has as one of its objects, the provision of a novel means for conveying fruit, the construction being such that the fruit will be rolled through the machine, instead of being bumped through it by an obviously undesirable lifting and dropping action, the fruit being rolled adequately, nevertheless, so that all portions of the fruit may be subjected to the discharge from a washing instrumentality (forming no part of the present application), should it be desired to wash the fruit.

The invention aims to improve the construction of the conveyers, the means for mounting them, and the means for actuating them, to the end that the result above referred to may be consummated.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

30 In the accompanying drawings:

Fig. 1 shows in side elevation, a device constructed in accordance with the invention;

Fig. 2 is a top plan;

Fig. 3 is a longitudinal section;

35 Fig. 4 is an end elevation;

Fig. 5 is a transverse section;

Figs. 6 to 10 are diagrammatic views illustrating the operation of the conveyers.

In Figs. 1, and 3, the letter A designates the forward end of the machine forming the subject matter of this application, the rear end of the machine being marked by the letter B.

The device shown and described comprises a box-like casing 1, which may be open at both ends, at the top and at the bottom. Extended across the lower portion of the casing 1 are cross beams 2 and 3, to which are secured the longitudinal bars 4 of a first conveyer, the bars operating within the casing 1. The bars 4 have inverted V-shaped teeth 5, as Figs. 6 to 10 will make manifest.

A cross beam 6 is located in front of the cross beam 2, and a cross beam 7 is located in front of the cross beam 3. To the cross beams 6 and 55 7 are secured longitudinal bars 8, forming part

of a second conveyer, the bars 8 of the second conveyer alternating with the bars 4 of the first conveyer, transversely of the machine, as disclosed in Fig. 2. The bars 8 of the second conveyer are supplied with inverted V-shaped teeth 9. Side pieces 10 extend practically the entire length of the machine and are secured to the cross beams 6 and 7 of the second conveyer.

A drive shaft 11 is journaled for rotation on the casing 1, near the rear end thereof, and is operated by any appropriate means indicated at 12. A driven shaft 14 is journaled for rotation on the rear portion of the casing 1, slightly in advance of the drive shaft 11, the shafts 11 and 14 being operatively connected by intermeshing gears 15.

An operating shaft 16 is mounted to rotate in the casing 1, near the lower rear corner of the casing, as shown in Fig. 1, the operating shaft 16 being arranged parallel to the shafts 14 and 11. A chain and sprocket drive 17 connects the shaft 14 with the shaft 16. There are crank disks 18 on the ends of the shaft 16, externally of the casing 1. The rear ends of pitmans 19 are pivoted to the crank disks 18, the forward ends of the pitmans being pivotally connected to the ends of the cross beam 2 of the first conveyer 2—3—4.

Rear rocker arms 21 are disposed externally of the casing 1. The lower parts of the rear rocker arms 21 are pivotally mounted at 22 upon the casing. The forward ends of connecting rods 23 are pivotally connected to the upper portions of the rear rocker arms 21, the rear ends of the rods 23 being pivoted to crank disks 24 on the ends of the driven shaft 14. Turn buckles 25 (or equivalent devices) are interposed in the connecting rods 23, to the end that the connecting rods may be adjustable as to length.

The upper ends of hangers 26 are pivoted to the rear parts of the rear rocker arms 21, the lower ends of the hangers 26 being pivoted to the ends of the cross beam 2 of the first conveyer 2—3—4. The upper ends of hangers 27 are pivoted to the forward portions of the rear rocker arms 21, the lower ends of the hangers 27 being pivoted to the ends of the beam 6 of the second conveyer 6—7—8.

Forward rocker arms 28 are provided, and their lower parts are pivotally mounted at 29 on the sides of the casing 1. The rear ends of substantially horizontal links 30 are pivoted to the upper portions of the rear rocker arms 21, the forward ends of the links 30 being pivoted to the upper portions of the forward rocker arms 28.

The upper ends of hangers 31 are pivoted to the rear portions of the forward rocker arms 28, the lower ends of the hangers being pivoted to the end portions of the cross beam 3 of the first conveyer 2-3-4. Hangers 32 are disposed in advance of the hangers 31, the upper ends of the hangers 32 being pivoted to the forward parts of the forward rocker arms 28, and the lower ends of the hangers 32 being pivoted to the ends 10 of the cross beam 7 of the second conveyer 6-7-8.

Radius arms 33, of considerable length, have their rear ends pivoted to the ends of the cross beam 7 of the second conveyer 6-7-8. The 15 forward ends of the radius arms 33 are pivotally mounted at 34 on the side walls of the casing 1. The radius rods 33 have small inclination with respect to the horizontal, the radius rods 33 are of considerable length, and, consequently, as the 20 rear ends of the radius rods, together with the beam 7 of the second conveyer 6-7-8 move up and down, the horizontal component in that movement is inappreciable.

The drive is initiated at the means 12, which 25 imparts rotation to the drive shaft 11. From the drive shaft 11, rotation is imparted to the driven shaft 14 by the intermeshing gears 15. From the shaft 14, rotation is imparted to the operating shaft 16 by the chain and sprocket drive 17. 30 The crank disks 18 on the ends of the shaft 16 operate the pitmans 19, and the pitmans impart a horizontal component to the movement to the first conveyer 2-3-4.

The shaft 14, the crank disks 24, the connecting rods 23, the rear rocker arms 21 and the hangers 26 give a vertical component to the movement of the first conveyer 2-3-4, and the hangers 27 give a vertical component to the movement of the second conveyer 6-7-8. From the 40 rear rocker arms 21, motion is transmitted to the forward rocker arms 28 by way of the links 30. The forward rocker arms 28 swing on their pivotal mountings 29, the hangers raise and lower the first conveyer 2-3-4, and the hangers 32 raise 45 and lower the second conveyer 6-7-8. It is to be observed that the second conveyer 6-7-8 has practically no horizontal movement, owing to the provision of the radius rods 33. The first conveyer 2-3-4, however, is not restrained by 50 any structure corresponding to the radius rods 33, and has in its movement a horizontal component due to the throw of the crank disks 18 on the shaft 16. Practically speaking, the second conveyer 6-7-8 moves up and down only, where-

as the first conveyer 2-3-4 has an elliptical or orbital movement in a clockwise direction.

In order that such words as "forward," "rear," "backwardly," and the like, in the following paragraph, may be understood clearly, it will be well 5 to note again at this point, by reference to Fig. 1, that the arrow A designates what is called the forward end of the machine, the rear end of the machine being designated by the arrow B.

Recalling that the second conveyer 6-7-8, 10 represented by the teeth 9 in Figs. 6 to 10, has, in substance, a vertical movement only, due to the provision of the radius rods 33 of Fig. 1, whereas the first conveyer 2-3-4, represented by the teeth 5 in Figs. 6 to 10, has a clockwise 15 elliptical orbital movement, including both horizontal and vertical components, the fruit introduced at the forward end of the machine may be regarded as being lodged between the teeth 9 of the second conveyer 6-7-8, as shown at 35 20 in Fig. 6. Then the fruit is eased down along the rear edges of the teeth 5 of the first conveyer 2-3-4 as indicated at 36 in Fig. 7, lodged in the angles between the teeth 5, as shown at 37 in Fig. 8 and passed over the teeth 9 of the conveyer 6-7-8, lodged between the teeth 9 and moved upwardly along the forward edges of the teeth 5, as indicated at 38 in Fig. 9, and finally carried over the teeth 5, as at 39 in Fig. 10, the cycle 30 being repeated until the fruit passes out of the rear end of the machine.

It will be noted that, although the fruit is rolled through the machine, there is no bumping of the fruit, the combined rolling and advancing movement of the fruit taking place as a gentle, advancing progression.

Having thus described the invention, what is claimed is:

In a device of the class described, a casing, first and second conveyers disposed side by side in the casing and having upstanding teeth, duplicate mechanisms connected to the conveyers for imparting up and down movement thereto in parallel planes, radius arms pivoted to the second conveyer and to the casing and constituting means for constraining the second conveyer against horizontal right line reciprocation, means cooperating with one of said mechanisms for imparting elliptical movement to the first conveyer, an operating connection between said mechanisms, and driving means connected to one of said mechanisms.

OREN E. BOGART.
